UNITED STATES PATENT OFFICE.

JORAM ZIEGLER, OF HARRISBURG, PENNSYLVANIA, ASSIGNOR TO ELLIOTT-FISHER COMPANY, OF NEW YORK, N. Y., A CORPORATION OF DELAWARE.

PAPER-FOLDING MACHINE.

1,003,023.

Specification of Letters Patent. Patented Sept. 12, 1911.

Application filed December 31, 1906. Serial No. 350,175.

To all whom it may concern:

Be it known that I, JORAM ZIEGLER, a citizen of the United States, residing at Harrisburg, in the county of Dauphin and State of Pennsylvania, have invented a new and useful Paper-Folding Machine, of which the following is a specification.

This invention relates to paper-folding machines of that type in which a long web of paper is continuously fed forward and folded longitudinally in opposite directions along a plurality of longitudinal lines to produce a manifold strip comprising longitudinal sections folded back and forth upon one another in a transversely zig-zag formation.

The object of the invention is to produce a simple and efficient apparatus comprising a folding grid of novel construction operating upon a paper strip to fold the latter as it passes from a delivery drum to a receiving drum; and to provide a receiving drum and operating means therefor so constructed that the folded strip or web will be wound into an approximately diamond-shaped package which may be readily folded flat for transportation or caused to assume a substantially square or rectangular form to facilitate the unwinding thereof when in use.

A further object of the invention is to provide tension mechanism operating on the paper strip to create sufficient tension upon the latter to cause it to wind comparatively smoothly and evenly upon the receiving drum.

A still further object of the invention is to equip a machine of this character with paper cutting mechanism by means of which the folded strip may be separated after a sufficient length of the latter has been wound upon the receiving drum.

Other objects subordinate to those enumerated will appear as the succeeding description of the illustrated embodiment of the invention is developed.

In the accompanying drawings, Figure 1 is a plan view of the complete machine. Fig. 2 is a longitudinal sectional view thereof. Fig. 3 is a detail perspective view of the grid with the folded paper strip in section. Fig. 4 is a sectional view of the rear end of the table and of the tension mechanism, cutter and receiving drum. Fig. 5 is a detail perspective view of the upper grid section detached. Fig. 6 is a

similar view of the lower grid section. Figs. 7 and 8 are detail views of the creasing or fold-compressing devices. Fig. 9 is a sectional view through the delivery drum and its supports. Fig. 10 is a side elevation of the same subject-matter. Figs. 11, 12, 13, 14, 15 and 16 are sectional views on the lines 11—11, 12—12, 13—13, 14—14, 15—15 and 16—16 of Fig. 2, showing progressive stages in the folding of the strip as it passes through the grid. Fig. 17 is a detail perspective view of a portion of the folded paper strip. Fig. 18 is a detail sectional view of the receiving drum with a portion of the strip wound thereon. Fig. 19 is a side elevation of the receiving drum showing the means for preventing rotation of the drum core on the shaft. Fig. 20 is a detail perspective view of the drum core, and Fig. 21 is a detail perspective view of the package core or holder.

Like characters of reference are employed to designate corresponding parts throughout the several views.

1 indicates a support or table having a top 80 terminating short of one end of the table and having its opposite end 3 inclined in a downward direction to produce an angle or corner 4. Above the table 1 is supported a folding grid 5 adapted to receive a paper strip or web from a delivery drum 6 between which, and the adjacent end of the grid, is located a guide roller 7. Beyond the opposite or delivery end of the grid 5 is supported a receiving drum 8 which is operated to draw the paper web through the folding grid from the delivery-drum and to wind it into the form of a package convenient for the subsequent use of the manifold strip thus produced. To insure sufficient tension on the paper strip *a* for the proper winding thereof on the receiving drum, tension mechanism in the form of a tension spring 9 is arranged to bear upon the strip at a point adjacent to the delivery end of the table. The tension mechanism is particularly necessary when the paper is comparatively thin and is therefore not subjected to any considerable tension by its passage through the grid. Between the tension mechanism and the receiving drum 8 is located paper cutting mechanism 10 by means of which the folded web or strip is severed when a sufficient length thereof has been wound upon the drum. Each of these 110

devices or mechanisms will now be considered in detail.

The delivery drum 6 comprises a shaft 6^a, rotatably supported by paired bearing rollers 6^b carried by bearing brackets 6^c adjustably retained by thumb nuts 6^d screwed upon the upper end of bolts 6^e passed upward through the frame of the table 1. (See Figs. 9 and 10.) The shaft 6^a carries core elements 6^f upon which is wound the paper roll a'. Also carried by the shaft adjacent to the outer ends of the core elements are heads 6^g retained in place by set collars 6^h and adapted to confine the opposite ends of the paper roll. This arrangement permits one of the heads to be readily removed from the shaft to facilitate the loading of the drum with the paper roll, after which the head is again secured in place. The rollers 6^b afford anti-frictional bearings for the drum and the adjustment of the brackets 6^c longitudinally of the table, permits the drum to be shifted slightly forward or back. As clearly shown in Fig. 1 of the drawings, the mounting of the guide roller 7 is identical with that of the drum 6 and therefore need not be described in detail. The paper folding grid 5 which is the primary element of the apparatus, comprises upper and lower grid sections 5^a and 5^b. The sections may be and preferably are formed of sheet metal and the section 5^a has its front end disposed horizontally and its rear end vertically, as shown in Fig. 5. It is constructed from a comparatively wide sheet of metal which is bent or otherwise formed to produce a central bottom wall 5^c which tapers toward the rear end of the grid. From one edge of this horizontal bottom wall 5^c rises a vertical wall 5^d which diminishes in height or tapers toward the front end of the grid section. A side wall 5^e extends from the upper edge of the central wall 5^d and is gradually twisted from a horizontal position at its front end 45 to a vertical position at its rear end. A somewhat similar side wall 5^f extends from one edge of the horizontal bottom wall 5^c, and, like the wall 5^e, is twisted to present its front end in a horizontal plane and its rear end in a vertical plane. The lower grid section 5^b is formed like the section 5^a, and comprises a bottom wall 5^g, a central vertical wall 5^h, and side walls 5ⁱ and 5^k, formed like the corresponding walls of the upper grid section, see Figs. 6 and 11. The lower grid section 5^b is provided at its opposite ends with lateral tabs 5^l carrying vertical studs 5^m which engage apertured tabs 5ⁿ projecting from the upper grid section 5^a to 55 maintain the upper and lower grid sections in proper relative positions. As the paper web passes between the grid sections, it is gradually folded into the form of a manifold strip, which, by reason of the vertical disposition of the rear end of the grid

proper, disposes it substantially vertical or edgewise to the table as it issues from between the sections 5^a and 5^b; see for instance Fig. 13. It is now desired to turn the manifold strip to a horizontal position and to incidentally complete the folding for the purpose of bringing the sections or layers of the strip into close contiguity, so that, as the strip passes on over the table to the tension, cutting and storing mechanisms, it will lie flat and closely folded. To attain this end, a grid extension 5° is disposed immediately in rear of the sections 5^a and 5^b. The grid extension is, or may be, merely a strip of sheet metal folded longitudinally to produce opposed walls 5^p and 5^q and twisted to present its opposite ends in right angularly related planes, the front end of the extension being disposed vertically and the rear end horizontally, as clearly shown in Fig. 6. As the paper strip a passes from between the grid sections 5^a and 5^b, the lower fold a'', the middle section or layer a', and one side section a³ of the manifold strip are received between the walls 5^p and 5^q of the grid extension 5°, while the upper edge of the wall 5^p is received within the upper fold a⁴ with the other side section a⁵ of the strip opposed to the outer side of the wall 5^p. Thus, as the strip is drawn through the grid extension, its sections are drawn close together, and it is turned from a vertical to a horizontal position, passing finally from the grid extension in substantially the form indicated in Fig. 3.

In order to compress or sharpen the opposite folds of the strip as the latter passes to the grid extension, oppositely disposed fold compressing devices 11 and 12 are disposed to engage the upper and lower or opposite folds a⁴ and a⁵ of the paper strip, at the front end of the extension 5°, see Fig. 13. The device 11 comprises a pair of diverging leaves 11^a and 11^b straddling the upper edge of the wall 5^p and having their front edges bent outwardly to form a flared guide for the paper fold. This device may be mounted in any effective manner, but is preferably carried at the outer end of a horizontal arm 13 pivoted upon a standard 14 rising from the table. As the upper fold of the paper passes through the fold compressing device 11 it is drawn close around the upper edge of the wall 5^p with sufficient pressure to cause a distinct creasing of the paper along the line of the fold so as to minimize any tendency to unevenness or irregularity of the line of the fold. The fold compressing or creasing device 12 is similar to the device 11, except that it does not straddle the wall of the grid extension, but is arranged to have its diverging leaves fitted into corresponding openings 15 in the walls 5^p and 5^q, see Figs. 6 and 13. The space between the diverging leaves of the device 12

forms a somewhat constricted passage through which the lower fold a'' of the paper passes and within which the fold is compressed in a manner to insure a closely folded flat formation of the manifold strip. The device 12 also differs from the device 11 in the manner of its mounting, being extended upwardly through an opening in the table, as shown in Fig. 13, and secured by bolts or other suitable means 16 below the table top. The manifold strip, now lying flat upon the table, passes forward to the inclined end 3 of the table, being incidentally drawn over the corner 4 which causes the further compression of its folds and insures a flat even juxtaposition of its layers or sections. When drawn over the inclined end portion 3 of the table, the manifold strip passes between a pair of guide blocks 17 which support the opposite ends of a bar 18 on which the tension spring 9 is mounted to bear at its free end upon the manifold strip.

Immediately beyond the tension spring 25 the cutter 10 is disposed, as heretofore stated, said cutter being in the form of a blade mounted to swing from one end and manipulated by a handle located at its opposite end. Normally the cutter 10 is held in an elevated position by a spring 19 to permit the free advance of the paper and is adapted to be swung down against the resistance of the spring to sever the paper when a sufficient quantity of the latter has been wound upon the receiving drum 8.

The receiving drum 8 comprises a pair of circular heads 20 and an intermediate transversely diamond shaped core 21 all mounted upon one end of a shaft 22 journaled in suitable bearings at the end of the table, as shown in Fig. 1, and driven by power applied thereto in any suitable manner and from any desired source, as for instance by a pulley 23 operated by a motor 40 driven belt 24. The heads 20 are retained on the shaft by set screws 25 and the core 21 is held against rotation relative to the heads by a latch 26 pivotally mounted upon the outer side of one of the heads 20 and engaging a stud 27 extended through the head from the drum, see Figs. 18, 19 and 20. In practice, a foldable paper holder 28 is placed upon the core 21, said holder being capable of conforming to the diamond shape 45 of the core during the winding of the manifold strip thereon. At one side of the holder 28 is formed a clip 29 by means of which the end of the strip is attached to the holder on the core. It will now be seen 50 that as the receiving drum is rotated, the manifold strip will be drawn from the delivering drum 6 and over the guide roller 7, thence through the grid proper, where it is folded longitudinally and delivered 55 to the fold compressing or creasing de-

vices and to the grid extension. As the paper is drawn through the grid extension it is turned down to a flat position upon the table and passed thence under the tension spring and cutter to the receiving drum, upon which it is wound. If the paper is of light weight and highly flexible, so that the tension produced by its frictional passage through the grid is insufficient to insure the close winding of the paper on the drum, the tension spring will present sufficient frictional resistance to the forward movement of the paper to cause the latter to be drawn tightly around the receiving drum as the latter rotates. When a sufficient length of paper has been wound on the drum the cutter 10 is swung down and the paper severed. The outer head 20 of the drum 8 is then removed, and the paper holder 28 with the manifold strip wound thereon, is slipped from the core. By reason of the foldable character of the holder the package formed by the holder and the paper wound thereon may be pressed flat to facilitate transportation. When it is desired to use the manifold strip stored on the holder, the latter may be pressed into a rectangular form so as to constitute in effect a hollow drum adapted to be placed upon a reel or the like to facilitate the unwinding of the stored paper strip.

It is thought that from the foregoing, the construction and operation of this paper folding machine will be clearly comprehended; but, while the illustrated construction is thought at this time to be preferable, I wish to reserve the right to effect such changes, modifications and variations thereof as may come fairly within the scope of the protection prayed.

What I claim is:—

1. In a paper folding machine, the combination with delivering and receiving mechanisms for a paper strip, of an intermediate grid arranged to fold the sheet in opposite directions along longitudinal lines, the rear end of the grid being disposed vertically, and means located beyond the rear end of the grid for turning the folded strip to a horizontal position.

2. In a paper folding machine, the combination with a paper folding grid having its front end disposed horizontally and its rear end disposed vertically, of a grid extension having its front end disposed vertically and its rear end horizontally, whereby a paper strip fed to the grid in horizontal position is folded along longitudinal lines and discharged from the rear end of the grid in vertical position and is subsequently turned again to a horizontal position.

3. In a paper folding machine, the combination with horizontal paper delivering and receiving devices, of an intermediate folding grid, and a grid extension ar-

ranged to receive the folded strip from the grid and having its opposite ends disposed in right angular relation.

4. In a paper folding machine, a grid having upper and lower members each formed with a rearwardly tapering bottom wall, a forwardly tapering central vertical wall rising from one edge of the bottom wall, and rearwardly converging side walls having their front ends substantially horizontal and their rear ends substantially vertical.

5. In a paper folding machine, a folding grid, comprising upper and lower sections, each formed with a rearwardly tapering bottom wall, a forwardly tapering central vertical wall rising from one edge of the bottom wall, and rearwardly converging side walls each having its front end disposed substantially horizontally and its rear end disposed substantially vertically, one of said side walls extending from one edge of the bottom wall and the other of said side walls extending from the upper edge of the central vertical wall.

6. In a paper folding machine, the combination with a paper folding grid comprising upper and lower sections each having a rearward tapered bottom wall, a forwardly tapered central vertical wall, and rearwardly converging side walls, said side walls having their front ends disposed in a substantially horizontal plane and their rear ends in substantially vertical planes, of a grid extension comprising walls having their front ends disposed vertically and their rear ends horizontally, whereby a horizontal paper strip may be folded along longitudinal lines to produce a vertically disposed manifold strip which is subsequently turned to a horizontal position.

7. In a paper folding machine, the combination with paper delivering and receiving devices, of intermediate paper folding mechanism, and a support for the paper strip, the rear end of said support being disposed at an angle to produce a corner

around which a folded paper strip is drawn by the paper receiving device to sharpen the folds in the paper.

8. In a paper/folding machine, the combination with a folding grid arranged to fold a strip of paper along longitudinal lines to produce oppositely disposed longitudinal folds, of separate and independent fold compressing devices located at the discharge end of the grid in position to compress the opposite folds respectively of the paper strip.

9. In a paper folding machine, the combination with a folding grid arranged to fold a paper strip along longitudinal lines to produce opposite longitudinal folds in said strip, of a grid extension arranged to turn the strip thus folded to a plane substantially at right angles to the plane in which the strip emerges from the grid.

10. In a paper folding machine, the combination with a folding grid arranged to fold a paper strip along longitudinal lines to produce opposite longitudinal folds in said strip, of a grid extension arranged to turn the strip thus folded to a plane substantially at right angles to the plane in which the strip emerges from the grid, and fold-compressing means associated with the grid extension.

11. In a paper folding machine, the combination with a folding grid arranged to fold a strip along longitudinal lines to produce oppositely disposed folds, of a grid extension arranged to turn the strip thus folded to a different plane from the plane in which the strip emerges from the grid, and oppositely disposed fold-compressing devices associated with the grid extension.

In testimony, that I claim the foregoing as my own, I have hereto affixed my signature in the presence of two witnesses.

JORAM ZIEGLER.
